UNITED STATES PATENT OFFICE.

ANDREW OSBORN, OF BRIDGEWATER, MASSACHUSETTS.

SHOE.

SPECIFICATION forming part of Letters Patent No. 651,555, dated June 12, 1900.

Application filed December 6, 1899. Serial No. 739,345. (No model.)

To all whom it may concern:

Be it known that I, ANDREW OSBORN, a citizen of the United States, residing at Bridgewater, county of Plymouth, State of Massachusetts, have invented an Improvement in Shoes, of which the following description, in connection with the accompanying drawings, is a specification, like letters on the drawings representing like parts.

10 My invention is an improved shoe, having for its object the provision of a relatively-inexpensive shoe which is protected and supported at the arch of the foot, being specially advantageous for skating and bicycle shoes and the like.

15 In carrying out my invention I provide opposite shank-supporting pieces secured externally of the vamp and stitched thereto and preferably forming a part of the welt in the case of welt-shoes.

20 The details of construction of my invention and further advantages thereof will be more particularly pointed out in the following description, reference being had to the accompanying drawings illustrative of a preferred embodiment of my invention.

25 In the drawings, Figure 1 is a bottom plan view of a shoe embodying my invention, parts being broken away to show the details of construction thereof. Fig. 2 is a broken view, in side elevation, showing a portion of a shoe provided with my improvement. Fig. 3 is a central transverse vertical section on the line 3 3, Figs. 1 and 2.

30 It will be understood that my invention is not limited to any particular style or kind of shoe, being herein shown as applied to an ordinary welt-shoe having an outer sole a , vamp a' , heel a^3 , inner sole a^4 , and suitable filling a^5 .

35 As herein shown and as preferably made, my invention is applied to a hand-sewed shoe, although it may be used in any machine-made shoe, if desired.

40 At the opposite sides of the shank a^6 of the sole I secure, as indicated, stiffening-pieces $a^7 a^8$, preferably of considerably-stiffer leather than that of the vamp a' , this leather being preferably of the same character as the outer sole a , although thinner, and shaped to the 45 contour of the foot, so as to perform the double function of protecting the vamp and stiffening or supporting the shank of the foot.

These pieces $a^7 a^8$ are stitched to the outside of the vamp, as indicated at a^9 , preferably by stitches passing through and through the 55 vamp a and lining a^{10} and being properly secured at their lower innermost edges to the shoe, being herein shown as secured by stitches a^{12} to the vamp or upper a and thereafter by stitches a^{13} to the outer sole in the 60 manner usual in welt-shoes. The usual welt a^{14} of the shoe terminates adjacent the stiffening-pieces $a^7 a^8$ and preferably overlaps the latter slightly, as indicated at a^{15} , the stiffening-pieces coöperating therewith in 65 forming a neat, light, and graceful shank at the sole. The opposite end of the stiffening-pieces extends, preferably, somewhat under the heel portion of the shoe, as indicated at a^{16} , thereby giving a strong support and also 70 coöperating with the parts already described in providing the shoe with a water-tight arch, this being the part of the shoe which is ordinarily the most apt to admit water to the foot. The stiffening-pieces are gracefully curved 75 at their upper edges and project sufficiently high along the vamp to give all the supporting and stiffening advantage required, together with proper protection of the vamp against cutting and abrasion, such as commonly occurs, especially in bicycle-riding, 80 skating, golf-playing, &c.

In riding the bicycle the foot is liable to slip on the pedal, thereby abrading and sometimes cutting into the thin leather of the 85 vamp at the arch of the shoe, this being particularly true of light shoes, such as kids, and other tender-grained shoes, such as those sometimes worn by ladies. The same is also true of walking across fields in playing games, 90 inasmuch as stubble, briers, flinty stones, &c., are very liable to cut into and injure the overhanging arch portion of the vamp.

95 My protectors $a^7 a^8$ effectually prevent the injury spoken of, while at the same time giving material support to the foot and to the shoe, so as to maintain the latter in the proper graceful lines desired. My improvements also keep the ankle from turning, and thereby tend to prevent the heel from running over. 100

While I have shown my invention embodied in a preferred form and having a particular cut desired, I wish it understood that I am not limited in all particulars thereto,

inasmuch as many modifications may be resorted to without departing from the spirit and scope of my invention.

I am aware that it is not new to provide 5 simply a stiffening device at the shank of a shoe, such devices, however, so far as I am aware, having served this purpose solely and having been either entirely distinct from the shoe, being properly surgical appliances, or 10 when provided in connection with a shoe they have been on the inside of the shoe next to the foot.

It will be understood that I have used the 15 shoe in this specification and in the claims in the generic sense, including any kind of foot-gear, whether boot or shoe.

Having described my invention, what I claim, and desire to secure by Letters Patent, is—

20 1. A shoe comprising a vamp, a welt, and an outer sole, the welt terminating adjacent the forward part of the shank of the shoe,

and an external piece of heavy, stiff, non-pliable material extending from adjacent the end of said welt to the heel, and being secured to the outside of the vamp and between the vamp and outer sole, substantially as described. 25

2. A shoe having opposite combined stiffeners and protectors secured at the shank of the shoe and extending externally of the vamp so as to cover and protect the latter in the region of the shank part thereof, and extending under the heel at their rear ends and between the sole and vamp and stitched to 30 the vamp, substantially as described. 35

In testimony whereof I have signed my name to this specification in the presence of two subscribing witnesses.

ANDREW OSBORN.
